[57] CLAIM

The ornamental design for a side fairing, as shown and described.

DESCRIPTION

FIG. 1 is a front perspective view of a side fairing showing my new design, it being understood that the broken lines are for illustrative purposes only and form no part of the design;

FIG. 2 is a front elevation view thereof;

FIG. 3 is a rear elevation view thereof;

FIG. 4 is an outer side elevation view thereof; and

FIG. 5 is an inner side elevation view thereof.
